(57) **CLAIM**

The ornamental design for an herb and vegetable extruder, as shown and described.

DESCRIPTION

FIG. 1 is a top perspective view of an herb and vegetable extruder, according to a first embodiment;

FIG. 2 is a top plan view thereof;

FIG. 3 is bottom plan view thereof;

FIG. 4 is a front plan view thereof;

FIG. 5 is a back plan view thereof;

FIG. 6 is a first side plan view thereof; and,

FIG. 7 is a second side plan view thereof.
